UNITED STATES PATENT OFFICE.

DWIGHT W. BENNETT, OF BRIDGEPORT, CONN., ASSIGNOR TO CRAIGHEAD & ELWELL MANUFACTURING COMPANY, OF SAME PLACE.

LAMP-FIXTURE.

SPECIFICATION forming part of Letters Patent No. 280,441, dated July 3, 1883.

Application filed September 7, 1882. (No model.)

To all whom it may concern:

Be it known that I, DWIGHT W. BENNETT, of Bridgeport, in the county of Fairfield and State of Connecticut, have invented a certain 5 new and useful Improvement in Lamp-Fixtures, of which the following is a specification.

This improvement relates particularly to hanging lamps of the kind wherein a so-called "harp" or "frame" is employed to 10 support the reservoir, and has connected to it the holder for the shade.

One feature of the improvement relates particularly to the support for the reservoir.

The improvement therefore consists in the 15 combination, with a cast-metal harp or frame, of a stud adapted to receive the lamp-reservoir upon it, and cast with or into the said harp or frame, and a plate fitted to the said stud, and secured thereon by a projection on one entering 20 a recess in the other.

Another feature of the improvement relates to the connection of the harp or frame and the shade-holder.

The improvement therefore further consists 25 in the combination, with buttons having a swiveling connection relatively to the upper ends of the harp or frame, of slots in the shade-holder through which the buttons may pass, and over which they may afterward be turned 30 to secure the parts together. Preferably inclined or wedge-like surfaces are provided on the shade-holder, so that the buttons may when turned thereon forcibly draw the harp or frame and shade-holder together.

35 The improvement also consists in the combination, with the hanger and pulleys for suspending-chains, of bearings for the journals of said pulleys, and wires secured by casting at the sides of said bearings, and bent over said 40 journals to secure them in the bearings.

In the accompanying drawings, Figure 1 is 45 a sectional side view of a lamp-fixture embodying my improvement. Fig. 2 is a top view of a part of the same. Fig. 3 is a top view of the hanger. Fig. 4 is a detail view illustrative of a modification of certain parts, and Fig. 5 represents a detail perspective view on a larger scale, showing how the journals of the pulleys are held in their bearings.

50 Similar letters of reference designate corresponding parts in all the figures.

A designates the harp or frame of the fixture. It is made of cast-iron or other metal.

B designates a stud adapted to receive upon it a lamp-reservoir having in the bottom a 55 socket of suitable size to fit upon it.

C designates a metal plate having a central opening, and adapted to be fitted over the stud B and support the bottom of a reservoir fitted on the stud. This plate is prevented from 60 turning on the stud by means of a teat or teats, a, on the one entering a recess, b, in the other.

At the upper ends of the harp or frame are buttons D, whose shanks have a swiveling connection with the same. They are preferably 65 cast in their swivel-bearings by the use of parting-sand, which is subsequently removed.

E designates a shade-holder, which may be made of cast metal and provided with any suitable devices for securing a shade to it. In 70 this shade-holder are slots c, through which the buttons D, when properly turned, may pass. After these buttons are passed through the said slots they may be turned across the same to secure the harp or frame and shade-holder 75 together. On the upper side of the shade-holder, adjacent to the slots, are inclined or wedge-like surfaces d, by acting upon which the buttons may be made to draw and clamp the harp or frame and shade-holder together. 80

G designates a plate fitted to the upper side of a plate, F, and having arms or extensions, which at the outer ends are provided with bearings e for the journals of the pulleys H. The plate G is secured to the plate F by a bolt, 85 I, and the bearings e impinge on the shade-holder.

In Fig. 4, I have shown bearings e, which have cast into them wires f, which, after the insertion of the journals of the pulleys, may 90 be bent down over them, so as to retain them in place, as best shown in Fig. 5. The suspending-chains, which are used in conjunction with these pulleys, may be of any suitable kind, and can be attached to any suitable counter-balance-weight after passing over the pulleys H of the hanger. 95

It will be seen that by my improvement I very materially cheapen the production of the lamp-fixtures and greatly improve them. 100

The shade-holder may be transported detached from the harp or frame, and connected

to the same, on the arrival of the parts at their destination, by even a person having little or no mechanical skill.

What I claim as my invention, and desire to 5 secure by Letters Patent, is—

1. The combination, with a cast-metal harp or frame, of a stud cast with or into the same and adapted to receive the lamp-reservoir upon it, and a plate fitted to the stud and secured 10 thereon by a projection on one entering a recess in the other, substantially as specified.

2. The combination, with a harp or frame provided with buttons having a swiveling connection relatively thereto, of a shade-holder 15 provided with slots through which the buttons may be passed and across which they may be turned, substantially as specified.

3. The combination, with a harp or frame provided with buttons having a swiveling connection therewith, of a shade holder provided 20 with slots through which the buttons may be passed, and inclined or wedge-like surfaces forming bearings for the buttons adjacent to the slots, substantially as specified.

4. The combination, with a hanger and pulleys 25 for suspending-chains, of bearings for the journals of said pulleys, and wires secured by casting at the sides of said bearings, and bent over said journals to secure them in the bearings, substantially as specified.

DWIGHT W. BENNETT.
